UNITED STATES PATENT OFFICE.

AUGUST SUNDH, OF HASTINGS UPON HUDEON, NEW YORK, ASSIGNOR TO OTIS ELEVATOR COMPANY, OF JERSEY CITY, NEW JERSEY, A CORPORATION OF NEW JERSEY.

TRACTION-ELEVATOR.

1,047,330.

Specification of Letters Patent.

Patented Dec. 17, 1912.

Original application filed June 27, 1907, Serial No. 380,990. Divided and this application filed June 23, 1911. Serial No. 634,823.

To all whom it may concern:

Be it known that I, AUGUST SUNDH, a citizen of the United States, residing at Hastings upon Hudson, in the county of 5 Westchester and State of New York, have invented a new and useful Improvement in Traction-Elevators, of which the following is a specification.

My invention relates to frictional drive. 10 apparatus, particularly adapted for use with and as forming part of traction elevators, and like apparatus.

This application is a division of my co-pending application, Serial #380,990, filed 15 June 27, 1907.

In a direct drive elevator system, commonly known as a traction elevator, and where a friction sheave on the hoisting motor shaft imparts motion to the elevator car 20 and counter-balance directly, that is, without the intervention of a winding drum and the worm gear, it is of the greatest importance that there shall be no slipping of the cables in relation to the hoisting or driving 25 sheave. The necessity for some remedy which will effectually remove this chief objection to traction elevators is well known to those versed in the art. The present invention aims to overcome this objection by 30 providing a facing of leather or like material for the hoisting cables, said facing being interposed between the drive sheave and the cables, so that the tension and strain are taken up by the cables, while, at the same 35 time, the leather facing furnishes a good friction contact.

Other objects of the invention and the precise nature thereof will appear more fully hereinafter.

Referring to the accompanying drawings, 40 Figure 1 illustrates a traction elevator, embodying the present invention; Fig. 2 is a fragmentary view, showing a portion of a drive sheave with a leather facing; Fig. 3 45 is a fragmentary view of the hoisting cables and the facing applied thereto; Fig. 4 is a sectional view of Fig. 3.

As shown in Fig. 1, the elevator car 1 is suspended by the hoisting cables 2 which 50 run on overhead sheaves 10 and 9, mounted on the supporting beam 11, and the drive sheave 7, secured to the shaft 13 of a motor 3. The usual counter-weight 6 is secured to

the opposite ends of the cables. A belt or facing 5 of leather, or other suitable material, is interposed between the cables 2 and the frictional driving sheave 7. This belt 5 as shown is in one continuous length, and is preferably fastened loosely to the cables by means of straps 4, the latter being fastened by rivets 12 to the belt 5. Where the belt 5 is found to stretch more than the cables 2, it is advisable to loosely rivet the straps 4, thereby allowing the belt to run smoothly, without buckling. Should, however, the belt stretch in the same proportion as the cables, the straps may be tightly riveted. This will depend to a large extent, upon the duty and strain upon the cables.

Fig. 2 illustrates a leather lining 8 applied to the traction surface of the friction drive sheave 7. This is for the purpose of further increasing the tractive effect.

Where a belt is used for power transmission, whether it be of leather, rubber, cotton or other material, it is, as is well known, subjected to great wear, where the tensile strain on the belt is considerable. Where the tensile strain is reduced to little or nothing, it is found that there is practically no wear at all. It is also well known that in elevator practice, where the steel cables run in contact with the traction sheave, there is considerable slipping, due to lack of sufficient friction or adhesion between the cables and sheaves. This slipping is highly objectionable for various reasons. It causes rapid wear of the cables, necessitating frequent and expensive repairs. It lowers the efficiency, and prevents complete and positive control of the elevator, thereby introducing an element of danger, and reduces the speed and accuracy with which the elevator may be operated and controlled, and is otherwise objectionable. By the use of the present invention, as above explained, these objections are overcome and the advantages of the use of both the steel hoist cables, and the leather belting are obtained without the disadvantage or objectionable features incident to the use of either alone. Furthermore, in the case of an arrangement as herein shown, the belt 5 partially balances the weight of the steel cables. The length of the belting is somewhat more than the run of the car, that is, it is of such length as to remain in con-

tact with the drive sheave throughout the travel of the car, but does not extend to the portions of the cables running on the overhead sheaves.

5. I wish not to be limited to the precise construction and arrangement of parts herein shown, as various changes might be made without departing from the spirit and scope of my invention.

10. What I claim as new and desire to secure by Letters Patent of the United States is:—

1. In an elevator, the combination with a car, of a counter weight, a cable uniting the car and counterweight, a pliable facing for a portion of the cable, and a driving pulley in frictional engagement with the pliable facing.

2. In an elevator, the combination with a driving motor, of a driving pulley connected thereto, a car, a counterweight, a cable uniting the car and counterweight, and passing around the driving pulley and a belt secured to the cable and interposed between the driving pulley and the cable.

25. 3. In an elevator, the combination with a car, a counterweight and a cable or cables connecting the car and counterweight, of a drive pulley or sheave associated with said cables, and leather facings on the pulley and cables in frictional engagement with each other.

35. 4. In a traction elevator, the combination with a car, a counterweight, and a cable or cables uniting the car and counterweight, of a flexible facing for a portion of the said cables, a drive pulley or sheave, and a leather facing for said sheave, said leather facing being in frictional driving engagement with the flexible facing of the cables.

40. 5. In an elevator, the combination of a car, a hoisting cable, a drive sheave, and leather facings interposed between the drive

sheave and cable and secured respectively to the sheave and cable.

6. In an elevator, the combination of a 45 car, a hoisting cable, a drive sheave, and a leather facing carried by the cable and automatically adjustable thereon to compensate for relative stretching of the cable and facing. 50

7. In an elevator, the combination of a car, a counterweight, a drive sheave, a plurality of cables, connecting the car and counterweight and extending around the drive sheave, and a strip of leather forming 55 a facing for the cables and interposed between the cables and drive sheave.

8. In an elevator, the combination of a car, a counterweight, cables connecting the car and counterweight, a drive sheave 60 around which the cables extend, and a leather facing carried by the cables and partially counter-balancing the cables.

9. In an elevator, the combination of a car, a counterweight, direction sheaves, cables connecting the car and counterweight, and running in direct contact with said sheaves, a drive sheave, and a leather facing 65 for the cables positioned to run in continuous contact with the drive sheave. 70

10. In an elevator, the combination of a car, a counterweight, cables uniting the car and counterweight, a driving pulley, and a pliable facing for the cables in frictional engagement with the driving pulley and substantially co-extensive with the portion of the cables running on the drive pulley. 75

In testimony whereof, I have signed my name to this specification in the presence of two subscribing witnesses.

AUGUST SUNDH.
